UNITED STATES PATENT OFFICE.

WILLIAM HENRY GRIFFITH, OF OMAHA, NEBRASKA.

WIRE FENCING.

No. 834,379.

Specification of Letters Patent. Patented April 14, 1908.

Application filed August 9, 1906. Serial No. 329,818.

To all whom it may concern:

Be it known that I, WILLIAM HENRY GRIFFITH, a citizen of the United States, residing in Omaha, in the county of Douglas and State of Nebraska, have invented certain new and useful Improvements in Wire Fencing, of which the following is a specification.

This invention relates to wire fencing or fabric formed of wires or the like material in which there are weft and warp wires, or wires running longitudinal and other wires running transversely thereto, either perpendicular or diagonally. Where two or more of these wires cross or intersect, a knotted joint is made, and the object of the present invention is to provide improved forms of such joints or knots that will very tightly secure the several wires against lateral movement.

A further object of the invention is to provide knots in the nature of hard knots that will not pull out or unlock, no matter how great a strain may be placed upon the wires endwise.

In the accompanying drawing illustrating embodiments of my invention, Figure 1 is a view illustrating three horizontal wires and four transverse wires that extend diagonally, the three wires crossing in each joint and being convoluted to secure the knot. Fig. 2 is a rear view of the joint shown at the top in Fig. 1. Fig. 3 is a view of the joint shown in Fig. 1, with the two diagonal wires removed. Fig. 4 is a rear view of the joint shown at the lower part of Fig. 1. Fig. 5 is a view of the same joint as shown in Fig. 1, but with the diagonal wires removed. Fig. 6 shows a joint similar to those shown in Fig. 1. Fig. 7 is a rear view of the joint shown in Fig. 6; and Fig. 8 is a view of the joint shown in Fig. 6, but with the two diagonal wires removed.

In Fig. 1 is shown a portion of fabric of diamond shape, composed of three horizontal wires A, B and C, with transverse wires D, E, F and G. The horizontal wires are shown as parallel, and the transverse wires also extend parallel but diagonally to the longitudinal wires. The three sets of wires, or three wires intersect to form a knotted joint. In the joint formed by the intersecting wires A, D and F, the wires D and F are but slightly deflected or bent from their general direction. The wire A is

knotted about the other two wires, first making a complete convolution 3 about the wire D, then making a complete convolution 4 about the wire F. The wire then passes diagonally across the back of the joint and makes a convolution 5 around the wire F on the opposite side of the loop and thence makes a convolution 6 around the wire D; thereby forming a kind of square of four loops, the stay wires passing through the diagonal opposite loops or convolutions. The leg 7 then passes beneath the wire F, as does also the leg 8 of the longitudinal wire. The reverse form of this joint is shown in Fig. 2.

In Fig. 3 is shown the reverse view of the lower joint shown in Fig. 1 where the wires C, G and E intersect and are interlocked by the knot formed by the wire C. In this construction, the horizontal wire from the leg 2 first makes a complete convolution around the wire G at 3, thence passes across the back of the joint at 5 and makes a convolution 4 around the wire E. The wire then passes underneath the portion 5 shown in Fig. 3 and makes a complete convolution around the wire E at 9. The wire at 6 passes along side the said portion 5 and makes a fourth convolution 8 around the wire G. From Fig. 3, it will be seen that the two crossing portions of the wire C are parallel at the middle of the joint.

In Figs. 4 and 5 is shown a very similar joint wherein two stay wires intersect a longitudinal wire with the latter wire convoluted once around each stay wire on opposite sides of the intersection. In this construction, the longitudinal wire A crosses the stay wires B and C, the wire A making the four convolutions 2, 3, 4 and 5 in the succession stated, and the wires crossing over being alternately above and below or interwoven as shown.

Having thus described my invention, I claim:

1. In a wire fence or fabric, a longitudinal wire and two diagonal stay wires, said three wires crossing at intervals and forming joints, the stay wires crossing without being looped, the horizontal wire first forming a complete loop around one of the stay wires 100 on one side of the joint, then crossing the knot and forming a convolution around the other stay wire, the knotted wire thence passing diagonally across the joint and being looped around the last mentioned stay wire, 110

the wire being thence passed across the knot and around the opposite side of the stay wire first looped.

2. In a wire fence or fabric, a longitudinal wire and two diagonal stay wires, said three wires crossing at intervals and forming joints, the horizontal wire first forming a complete loop around one of the stay wires on one side of the joint, thence crossing the knot and forming a convolution around the other stay wire, the knotted wire thence passing diagonally across the joint and being looped around the last mentioned stay wire, the wire being thence passed across the knot and around the opposite side of the stay wire first looped.

3. In a wire fence or fabric, a longitudinal wire and two diagonal stay wires, said three wires crossing at intervals and forming joints, the stay wires crossing without being looped, and on opposite sides of the knot, the horizontal wire first forming a complete loop around one of the stay wires on one side of the joint, thence crossing the knot and forming a convolution around the other stay wire, the knotted wire thence passing diagonally across the joint and being looped around the last mentioned stay wire, the wire being thence passed across the knot and around the opposite side of the stay wire first looped.

4. In a wire fence or fabric, a longitudinal wire and two diagonal stay wires, said three

wires crossing at intervals and forming joints, the two stay wires crossing without being looped, the horizontal wire being bent to form four loops, one of the stay wires passing through two of the loops and the other stay wire passing through the other two loops.

5. In a wire fence or fabric, a joint formed of three wires, two of the wires crossing without being looped and the third wire being bent to form four loops, one of the wires passing through two diagonally situated loops, the other passing through the other two diagonally situated loops.

6. In a wire fence or fabric, a joint formed of a plurality of wires, two wires crossing without being looped, and a third wire bent into a series of loops through which the other wires are respectively passed.

7. In a wire fence or fabric, a joint formed of three wires, two of the wires crossing without being looped and the third wire being bent to form four loops, one of the wires passing through two diagonally situated loops, the other passing through the other two diagonally situated loops, said third wire entering the knot on one side and emerging from the knot on the opposite side.

WILLIAM HENRY GRIFFITH.
